UNITED STATES PATENT OFFICE.

FINGAL CECIL ORR, OF STILLORGAN, IRELAND.

APPARATUS FOR PROPELLING SHIPS OR BOATS.

SPECIFICATION forming part of Letters Patent No. 789,334, dated May 9, 1905.

Application filed May 10, 1904. Serial No. 207,314.

To all whom it may concern:

Be it known that I, FINGAL CECIL ORR, engineer, a subject of His Majesty the King of Great Britain and Ireland and of the British Dominions Beyond the Seas, Emperor of India, residing at Amana, Stillorgan, in the county of Dublin, Ireland, have invented certain new and useful Improvements in Apparatus for Propelling Ships or Boats, of which the following is a specification.

This invention has reference to apparatus of the kind described in the specification in connection with my joint British Letters Patent No. 9,099 of A. D. 1902, with Mark Louis Orr for propelling ships, launches, boats, and other vessels, (all hereinafter referred to as "ships" and "boats.") In the said apparatus the ship or boat is propelled by the explosion at short intervals of time of gas or explosive vapor or petrol or other explosive material acting directly on the water through a pipe or pipes provided with non-return valves and opening out of the vessel ahead and astern below the water-line and arranged in such a manner that the expansion of the gases resulting from the explosion forces the water from the pipe or pipes at the stern or at the bows, according to which of the non-return valves is open, which has the effect of propelling the vessel in the opposite direction to that in which the water is being expelled.

My present invention consists principally of improvements in the construction of the combustion-chamber and parts immediately connected therewith whereby I am enabled to maintain the explosive charge in the combustion-chamber under any desired degree of compression until firing and then to act upon the water in the water-tube when the maximum explosive pressure has been reached, so that by this means I get the full benefit of the pressure due to the compression and explosion of the charge, and, moreover, after each explosion I am enabled to insure the pressure of the products of the previous combustion in the combustion-chamber falling to a low pressure, so as to insure economy in working.

Another part of my present invention consists of an improved form of ahead-valve which is automatic in its action and can read-

ily be set when desired to give a free passage through the water-tube when going astern.

My invention also comprises other minor improvements, as hereinafter described.

I will describe my invention by referring to the accompanying drawings, on which—

Figure 1 is a side elevation, partly in section, of a boat with propelling apparatus constructed in accordance with this invention. Fig. 2 is a longitudinal sectional elevation of the said apparatus on a larger scale. Figs. 3 and 4 are sectional plans of my improved ahead-valve, Fig. 3 showing the valve turned into the position which it occupies when the boat is going ahead, and Fig. 4 shows the ahead-valve turned one-quarter round, as when the boat is going astern. Fig. 5 is a plan of the apparatus shown by Fig. 2, but with part of the combustion-chamber broken away, so as to show the ahead-valve underneath. It is to be understood that my drawings only show such parts of the apparatus as are necessary to illustrate my present improvements.

The same letters of reference indicate the same parts in all the figures.

A is the combustion-chamber in which the explosive charge is fired.

B is the outlet from the combustion-chamber, communicating with the water-pipe C' C² C³, which opens out of the vessel ahead at c' and astern c² below the water-line D.

In carrying out the first part of my invention the outlet B from the combustion-chamber A to the water-tube C' C² C³ is controlled by a mushroom or other suitable valve E, and immediately opposite this valve E the upper part of the combustion-chamber is formed as a cylinder F, fitted with a piston G, which is connected by the piston-rod g' to the valve E, so that the valve E and piston G can only move together. The area of the piston G and of the cylinder F is larger than the area of the valve E. The upper or outlet end of the cylinder F is closed by a suitable cylinder-cover f', in which is an inlet H, controlled by a spring or other suitable non-return valve h', opening inwardly and through which air or gas under pressure can be forced into the cylinder F on the top of the piston G, so as to close the valve E down onto its seating. The

- valve h' retains the air or gas pressure in the cylinder F. As the area of the piston G is larger than the area of the valve E, it follows that when the explosive mixture is forced into 5 the combustion-chamber A through the inlet a' the pressure in the combustion-chamber A will rise and act on the difference in area between the under side of the piston G and the top of the valve E until such a pressure is 10 reached that the pressure acting on this difference of area is sufficient to overcome the resistance in the opposite direction on the piston G, due to the pressure of the air or gas in the cylinder F on the top of the piston plus 15 the force of gravity due to the weight of the piston G and piston-rod g' and valve E. When this pressure is attained the piston G will begin to rise and lift the valve E off its seating, and thus open the passage B to the water-tube 20 C' C² C³. In practice, however, just before this pressure has been attained I fire the charge in the combustion-chamber A, which causes the pressure in the combustion-chamber to rise with a bound from the compression-pressure 25 (due to the pump or fan) to the maximum explosion-pressure, this sudden increase of pressure in the combustion-chamber causing the piston G to rise suddenly toward the top of the cylinder, and thus to open widely the 30 valve E from the combustion-chamber A to the water-tube C', so that the full force of the explosion-pressure is obtained on the water in the tube C' C² C³. As the explosive pressure in the combustion-chamber A now acts 35 on the under side of the valve E and neutralizes the pressure on the top of the same the whole area of the under side of the piston G becomes effective to the explosion-pressure, thus increasing the resistance of the pressure 40 of the compressed air or gas in the cylinder F on the top of the piston G, which is tending to close the valve E. Thus it will be seen that the pressure in the combustion-chamber A must now fall considerably below the original 45 compression-pressure before the pressure of the compressed air or gas in the cylinder F will be sufficient to force down the piston G and close the valve E. I thus insure economy in working, as the products of combustion remaining in the combustion-chamber A fall down to a very low pressure before the valve E closes and the next charge of explosive mixture is admitted.
- On the top of the combustion-chamber A 55 there is, as heretofore, the outlet I' for the escape of the products of combustion remaining from the previous charge and which are forced through the outlet I' by the next charge of explosive mixture entering the lower part 60 of the combustion-chamber a through the inlet a' . Above the outlet I' there is, as described in the specification of the prior British Letters Patent No. 9,099 of 1902, above referred to, the self-acting valve J, which is made to 65 be closed by the internal pressure in the com-

bustion-chamber, but which normally hangs open, the weight of the valve being partly counterbalanced by the spring j' . On the outside of the outlet I² from the valve J, I provide, according to part of my present invention, a spring-pressure valve K, which is similar to an ordinary modern marine safety-valve, and the spring k' of which is so set that it will allow this valve K to open only when the desired compression pressure in the combustion-chamber A is reached. Thus it follows that when the fresh charge is being forced into the combustion-chamber A through the inlet a' the products of combustion of the previous charge are forced through the outlet I' and valve J to the under side of the valve K, and when the desired compression pressure in the combustion-chamber A is reached the remaining products of combustion of the previous charge are forced through the valve K into 80 the atmosphere, and when the charge in the combustion-chamber A is fired the sudden increase of pressure momentarily closes the valve J so as to prevent the escape of the pressure except through the outlet B, and then as 85 the pressure in the combustion-chamber A falls again the valve J opens for the products of combustion to pass to the under side of the valve K.

My improved ahead-valve, which is arranged 95 in the fore end of the water-tube C', is made as follows: I provide a suitable cylindrical chamber L, having an inlet l' at one side and an outlet l'' at the other side with flanges to fix to the water-tube C', and in this cylinder 100 L, I provide two disks (marked, respectively, M' M²) arranged one above the other below the inlet and outlet passages l' l'' and connected together by a web or plate M³, having an opening fitted with a non-return valve N or 105 with two or more of the same. The upper disk M² has a spindle part m' projecting through the cover l³ of the chamber L and by which the disks M' M², with the non-return valve or valves N, can be turned so that the 110 web M³ will either be across the water-tube, as in Figs. 1, 2, and 3, or in a line therewith, as in Fig. 4. When the boat is going ahead, the disk parts M' M², with the non-return valve, are turned to the position shown in Figs. 115 1, 2, and 3, so that the web M³ is across the water-tube and the valve N or valves open inwardly toward the combustion-chamber A, so that the water entering the fore end c' of the water-tube can flow therethrough, but 120 cannot return. When the vessel is going astern, the disk part M' M² is turned to the position shown in Fig. 4—that is, at about right angles to the position which it occupies when the vessel is going ahead—so that the 125 web M³ will now be in line with the water-tube C', and there will be a clear passage therethrough.

In the stern portion of the water-tube C' 130 instead of employing a self-acting non-return

valve, as described in the prior British Specification No. 9,099 of 1902, above referred to, I may use a sluice-valve O, operated by a screwed spindle o' and hand-wheel o², so that when the boat is to go astern this sluice-valve O is closed, so as to shut off the stern portion of the water-tube and compel the water to flow forward past the ahead-valve N, which will then be turned to the position shown by Fig. 5. In order to facilitate the reversing of the motion of the vessel, the spindle m' of the ahead-valve may be so connected to the sluice-valve O that when the sluice-valve is raised to open the passage through the water-tube to the stern of the boat the web M³ of the ahead-valve will be turned to the position shown in Figs. 1, 2, and 3, so that the ahead-valve N will be operative to prevent the water flowing back through the water-tube C' 15 to the stern of the boat the web M³ of the ahead-valve will be turned to the position shown in Figs. 1, 2, and 3, so that the ahead-valve N will be operative to prevent the water flowing back through the water-tube C' 20 C³ ahead at the fore part of the ship, and when the sluice-valve is being closed then the connections from the sluice-valve to the ahead-valve turn the web of the latter to the position shown in Fig. 4, so that the water will 25 then be forced out at the fore part of the boat to propel it astern.

The means which I have shown on my drawings, Figs. 1, 2, and 5, for operating the sluice-valve and ahead-valve simultaneously, as above described, (but which means are only intended as an illustration and not as limiting my invention to this particular arrangement,) consist of an endless guy-rope P, which passes round sprocket-teeth o³, formed on the boss 30 of the hand-wheel o² of the sluice-valve, this part of the guy-rope being made as a gear-chain to gear with the sprocket-teeth. The guy-rope P is led over jockey-pulleys q' q² q³ q⁴ and around a grooved wheel m², which is 35 fixed on the spindle m' on the web M³ of the ahead-valve. There is a small ball p', fixed on the rope P to gear with a notch m³ in the sprocket-wheel m². Assuming that the sluice-valve O is open and the ahead-valve occupies 40 the position shown in Fig. 2, then by turning the hand-wheel o² through a small angle the endless rope P is moved, thereby turning the ahead-valve to the position shown in Fig. 4. The ball p' now rises out of the notch m³, 45 leaving the same at about right angles to the position shown in Fig. 5, and the movement of the hand-wheel is continued so as to close the sluice-valve O. By turning the hand-wheel o² in the opposite direction the sluice-valve O is opened, and at a short time before 50 the sluice-valve assumes its extreme open position the ball p' on the cord P arrives at and enters the notch m³ of the wheel m² of the ahead-valve and then turns the ahead-valve 55 back to the position shown in Fig. 3 ready for the boat to go ahead.

In order to keep the combustion-chamber A cool, I prefer to surround the same with a water-jacket R, through which cold water is 60 caused to circulate by any convenient means,

such water entering the jacket at r' in the lower part of the same and flowing out through the outlet r² in the upper part of the same.

In order to prevent as far as possible the shocks of the explosions in the combustion-chamber A being felt in the boat, I provide buffers, such as the spring-buffers T' T² U' U², where the energy is transmitted from the motor to the boat, so arranged as to absorb or partially absorb the shocks, as aforesaid, and 70 in order to allow of the motor having a little play in a fore-and-aft direction I provide two expansion-joints S' S² in the water-tube C' C² C³, arranged fore and aft of the motor. It will be understood that the motor, with the 75 portions marked C' of the water-tube, have by reason of the expansion-joints S' S² a small fore-and-aft movement independently of the aft portion C² of the water-tube, which by the thrust-brackets c³ c⁴ is fixed to the vessel. The 80 fore part C³ of the water-tube is also similarly fixed to the vessel by brackets c⁵ c⁶. The motor is kept in position by the two side rods V' V², which are situated at the sides of the motor and are fixed to and pass through lugs l³ 85 l⁴ on the sides of the ahead-valve L and slide through corresponding lugs c⁷ c⁸, formed on the sides of the fixed part C³ of the water-tube. These rods V' V² are also fixed to and pass through lugs c⁹ c¹⁰, formed on the sides of the 90 casing of the sluice-valve O, and then they pass and slide through lugs or brackets c⁹ c¹⁰, formed on the sides of the fixed stern portion C² of the water-tube, so that the buffer-springs T' T², which take the shock of the explosion 95 when the boat is going astern, are situated on the rods V' V² forward of the lugs c⁹ c¹⁰ and bear between the same and adjusting-nuts v' v², fixed on these rods. The other buffer-springs U' U², which I call the "ahead-springs," are also situated on these rods V' V² 100 astern of the lugs c⁹ c¹⁰ and bear between the same and nuts v³ v⁴, fixed on the ends of the rods V' V². Thus it will be seen that when the motor is in action the whole of the motor, 105 with its guide-rods V' V² and the portions C' of the water-tube, can slide fore and aft slightly in the bearings c⁷ c⁸ c⁹ c¹⁰ and that the shocks of the explosions in the combustion-chamber will be to some extent absorbed by 110 the springs T' T² U' U².

I have described my improvements as applied to a boat in which the water-tube runs right through from the stern to the bows; but it will be understood that, if desired, said water-tube may, as described in the specification of the prior British Letters Patent No. 9,099 of 1902, above referred to, instead of opening out at the extreme ends of the boat open out 115 through the sides of the same or through the keel.

What I claim as my invention, and desire to secure by Letters Patent, is—

1. In apparatus of the kind herein referred to for propelling ships launches boats and 120

- other vessels, the combination with the combustion-chamber of a valve controlling the outlet therefrom and a cylinder and piston of larger area than the valve said piston being connected to said valve so as to act therewith, said cylinder being open to the combustion-chamber at one side of the piston and communicating with an air or gas pressure at the other side of the piston so that air or gas under pressure can be forced into the cylinder to act on the piston and close the valve until after the charge of explosive mixture has been forced into and compressed in the combustion-chamber and fired when the increase of pressure in the combustion-chamber due to the explosion acts upon the difference in area between the piston and the valve and overcoming the air or gas pressure in the cylinder on the other side of the piston moves the piston and opens the valve and escapes to act upon the water in the water-tube and propel the vessel all substantially as set forth.
2. In apparatus of the kind herein referred to for propelling ships launches boats and other vessels provided with a combustion-chamber having an outlet-valve therefrom controlled by a piston operated by the pressure in the combustion-chamber, an outlet for the products of combustion remaining in the combustion-chamber from a previous charge, an internally-opening valve in said outlet which is normally open and is closed by the internal pressure in the combustion-chamber in combination with a valve opening outwardly in the said outlet and weighted by a spring so as to only open when the desired compression-pressure of the explosive mixture in the combustion-chamber has been attained said internally-opening valve being momentarily closed by the increased pressure in the combustion-chamber when the charge is fired, substantially as set forth.
3. In apparatus of the kind herein referred to for propelling ships launches boats and other vessels, the combination with the combustion-chamber of the valve E controlling the outlet therefrom, the cylinder F of larger area than the valve and formed with the combustion-chamber, the piston G fitting in said cylinder and connected to the valve E so as to move therewith, the cylinder-cover having an inlet H for admission of compressed air or gas to the back of the piston to close the valve, said cylinder having an outlet I for the escape of the products of combustion remaining from the previous charge, the valve J in said outlet opening inwardly and adapted to close the same when the charge in the combustion-chamber is fired, and the spring-weighted valve K adapted to only open for the escape of the products of combustion when the desired compression-pressure of the explosive

mixture in the cylinder has been reached, said parts being constructed and arranged for joint operation in the manner, substantially as set forth and illustrated.

4. In apparatus of the kind herein referred to for propelling ships launches boats and other vessels, the combination with the water-tube communicating with the combustion-chamber, of the improved ahead-valve therein having a cylindrical body and inlet and outlet communicating with the said water-tube and two disks one above and the other below said inlet and outlet connected together by a web 75 having an opening controlled by a self-closing valve and with a spindle projecting through the valve-casing and so arranged that the disks with the valve can be turned so as to either give a free passage in either direction through the water-tube or turned at about right angles to this position so as to allow the water to only flow in one direction, substantially as set forth.

5. In apparatus of the kind herein referred to for propelling ships launches boats and other vessels, the combination with the water-tube having two expansion-joints therein, said joints being arranged respectively fore and aft of the combustion-chamber so that the combustion-chamber and other operating parts of the motor are capable of a slight longitudinal movement in either direction independently of the outlet ends of the water-tube which are fixed to the vessel, in combination with springs 95 so arranged as to control the said longitudinal movement of the motor and absorb or partly absorb the shocks due to the explosions in the combustion-chamber, substantially as set forth.

6. In apparatus of the kind herein referred to for propelling ships launches boats and other vessels the combination with the combustion-chamber and its accessories and the portion of the water-tube to which they are 105 fixed, of the two expansion-joints S' S², the fixed end parts C' C² of the water-tube in which the part of the water-tube to which the combustion-chamber is fixed can slide, the side guide-rods V' V² fixed to and moving with the combustion part of the water-tube and sliding in guides formed on the fixed end portions of the water-tube, with the coiled springs T' T² U' U² on said rods so arranged as to absorb or partly absorb the shocks due to the 115 explosions in the combustion-chamber when the vessel is going ahead or astern, substantially as set forth.

In witness whereof I have hereunto set my hand in presence of two witnesses.

FINGAL CECIL ORR.
